UNITED STATES PATENT OFFICE.

THOMAS H. EULASS, OF MASON CITY, ILLINOIS.

IMPROVEMENT IN HEMMERS FOR SEWING-MACHINES.

Specification forming part of Letters Patent No. 96,901, dated November 16, 1869.

To all whom it may concern:

Be it known that I, THOMAS H. EULASS, of Mason City, Mason county, Illinois, have invented a new and useful Adjustable-Hemmer for Sewing-Machines; and I hereby declare the following to be a full, clear, and exact description thereof, reference being had to the accompanying drawings, making part of this specification.

My invention relates to a hemmer for sewing-machines which has the ordinary means of attachment and adjustment upon the cloth-plate, and which has also a means of adjustment, as hereinafter described, by which wider or narrower hems may be made at pleasure.

Figure 1 is a perspective view of my hemmer as constructed for use on the "Florence" sewing-machine. Fig. 2 is a transverse section of the same. Fig. 3 is a perspective view of my adjustable turning-plate, showing the form of the turning groove or rabbet.

The main portion of my hemmer is preferably formed from a single plate of sheet-brass, German silver, "white metal," or other suitable material. Its lower portion or base A lies flat upon the cloth-plate of the sewing-machine when in use, and is connected by a fold, a, with a portion, A', a part of which lies flat upon the base A, while a part extends beyond the base, as shown in Figs. 1 and 2. Connected with the portion A by a semicircularly-curved portion, B, is the scale-plate C, which plate has a slot, c, extending from the curved portion B to near the end of said plate, and upon each side of the slot is marked a scale, c'.

Between the two plates A' and C is introduced a turning piece or plate, E, formed of cast or sheet metal, as preferred, and having on one side a somewhat spirally-shaped groove or rabbet, e, which groove acts in conjunction with the under side of the scale-plate to turn the edge of the cloth.

The plate E has a screw-threaded hole, e',

for the reception of a thumb-screw, F, which passes through the slot e, and by which the piece E is secured, at the desired adjustment, to the plate C.

The base A has an extension or arm, G, having a slot, g, to admit the ordinary thumb-screw, by which the hemmer is secured to the cloth-plate of the machine.

By a slight modification of the arm G the hemmer is made to suit other sewing-machines besides the Florence.

The operation of my hemmer is as follows: The ends of the turning-piece E (which project slightly beyond the edges of the scale-plate C) are placed, by the scales c', to the desired width for the hem. The thumb-screw F is then tightened, so as to secure the turning-piece in place. The hemmer is then secured to the cloth-plate of the sewing-machine by means of the ordinary thumb-screw passing through the slot g. The edge of the cloth to be hemmed is passed between the turning-piece E and the portion A, and being turned over within the curved part B the immediate edge is turned by the rabbet in the piece E, thus forming a complete fold or hem, which is secured by stitching, in the ordinary manner.

It will be seen that by adjusting the turning-piece the hem may be made of any desired width within certain limits.

I claim—

As a new article of manufacture, the hemmer herein shown and described, consisting of plate A A' B C G, formed as described, and having slots c g, scales c' c', and adjustable edge-turning block E and set-screw F.

In testimony of which invention I hereunto set my hand.

THOMAS H. EULASS.
